PALLET

James R. Freund, Roslyn, Pa., assignor to Pennsylvania
Pacific Corporation, Warminster, Pa.

Filed Nov. 29, 1971, Ser. No. 103,118

Term of patent 14 years

Int. Cl. D12—99

U.S. Cl. D14—3 N

FIG. 1.

FIG. 4.

FIG. 5.

FIG. 2.

FIG. 3.

FIG. 6.

FIG. 1 is a top plan view of a pallet showing my new design, the bottom being the same,

FIG. 2 is a front elevation of the pallet,

FIG. 3 is a rear elevation of the pallet,

FIG. 4 is a right side elevation of the pallet,

FIG. 5 is a left side elevation of the pallet, and

FIG. 6 is a top perspective view, partially broken away, of the pallet showing somewhat more than the left front quarter, all four quarters of the pallet being the same.

I claim:

The ornamental design for pallet, as shown and described.
